[57] CLAIM

The ornamental design for a bowl or similar article, as shown and described.

DESCRIPTION

FIG. 1 is a top plan view of a bowl or similar article showing my new design;

FIG. 2 is a side elevational view thereof, with all sides being similar;

FIG. 3 is a bottom plan view thereof; and

FIG. 4 is a vertical transverse cross-sectional view thereof taken along line 4—4 of FIG. 1, looking in the direction of the arrows.

FIG. 1

FIG. 4
